UNITED STATES PATENT OFFICE.

FRANK S. ALIANO, OF NEW YORK, N. Y.

LOCK AND LATCH.

No. 887,053.

Specification of Letters Patent.

Patented May 12, 1908.

Application filed August 31, 1906. Serial No. 332,783.

To all whom it may concern:

Be it known that I, FRANK S. ALIANO, a citizen of the United States, residing at the borough of Brooklyn, in the city of New York, county of Kings, and State of New York, have invented certain new and useful Improvements in Locks and Latches, of which the following is a specification, reference being had therein to the accompanying drawings, which form a part thereof.

My invention relates to locks and latches and more particularly to a type of combined locks and latches which operate automatically.

The main object of the invention is to provide a combined lock and latch wherein the bolt will be normally "dead" when the lock is latched and cannot be drawn except through the use of a key or other means provided for this purpose, thus preventing the forcing of the lock through means applied to the bolt itself.

A further object is to provide such a lock wherein the dead lock mechanism, when the bolt is shot otherwise than in the bolt socket, will be capable of being automatically actuated through the movement of the bolt, to permit the latter to slide freely when it enters the socket, and to prevent movement thereof subsequently to the latching of the lock, except by a key or knob.

A still further object is to provide such a lock wherein a member independent of the bolt and not susceptible of movement there-by, will be interposed between the releasing mechanism and the bolt and between the bolt and the dead latch mechanism, thus making the operation of said last mentioned mechanism entirely independent of the bolt.

A still further object is to provide a lock of this character wherein any efforts to force the bolt will be transmitted directly to the lock casing, thus avoiding the use of studs, projections or other parts holding and absorbing the strains placed upon, the dead latch mechanism, and giving strength to the mechanism.

A still further object is to provide such a lock which will be entirely automatic in all its operations except when released through a knob or key. And a still further object is to provide a combined lock and latch which will operate positively, which will not be liable to disarrangement of parts and which will be simple in design and inexpensive to produce.

The invention consists primarily in an au-

tomatic combined lock and latch comprising a casing, a spring pressed bolt therein, shoulders on said bolt whereby it may be drawn within said casing, key or knob actuating means for said bolt, a detent adapted when said lock is latched to engage said bolt and prevent movement thereof, means interposed between said shoulders and said last mentioned means and adapted to release said detent, a reciprocating member adapted to be projected from said casing with the bolt when said bolt is disengaged from the socket, and to engage the edge of said socket and be forced within said casing when the bolt enters said socket, means actuated by said member whereby when said member is projected, said detent will be rendered inoperative and when it engages said socket, said detent will be set, and a bolt socket; and in such other novel features of construction and combination of parts as are hereinafter set forth and described and more particularly pointed out in the claims hereto appended.

Referring to the drawings: Figure 1 is a plan view of a combined lock and latch embodying my invention; Fig. 2 is an enlarged view of the sliding plate through which the bolt and the detent are actuated and of a part of the bolt and bolt releasing mechanism co-operating therewith; Fig. 3 is a section of the lock shown in Fig. 1 showing the lock mechanism in elevation; Fig. 4 is an enlarged cross section of the bolt and of the tongue actuating the latch plate when the bolt is being latched, and Fig. 5 is an enlarged plan view of said tongue.

Like letters refer to like parts throughout the several views.

In the embodiment of my invention shown in the drawings, I have shown an ordinary lock casing at *a* and a socket plate at *b*. Closing said casing is a cover *c*. The casing *a* has an ordinary bolt opening therein at *a'* and a smaller opening at *a''* communicating therewith. A sliding bolt *d* is mounted in said casing, the beveled end *d'* thereof being normally projected through said opening by the springs *d''* acting on the shank of said bolt against a plate *d'''* held in place by angular brackets *d''''* carried by said casing. This plate *d'''* acts both as an opposed bearing for the springs *d''* and an inner guide for the bolt shank. The shank of said bolt is forked as shown to provide clearance space for the operation of the bolt and suitable carriers for the springs *d''*. Each end of said bolt shank

is provided with an upwardly extended shoulder d^5 by means of which the bolt is actuated. The construction and arrangement of this bolt mechanism is well known and now 5 in extensive use and no claim of invention is made as to such. To prevent movement of said bolt independently of the releasing mechanism when the lock is latched, I provide means normally positioned in the path 10 of the shoulders d^5 preferably comprising a detent e pivotally mounted in the casing a with the rear edge thereof in close juxtaposition to the wall of said casing and the forward edge thereof positioned slightly away 15 from the rear of the said shoulders d^5 . The forward edge of said plate is normally pressed downwardly by a torsion spring e' mounted on the pivot pin e^2 of said plate, the ends of said spring acting respectively on the 20 casing a and on the plate e . Bearings for said pin are formed by turning downwardly portions of the plate as e^3 on opposite sides thereof and radially of said pin. The plate may be cut away as desired to provide 25 proper clearance for the cylinder lock and releasing mechanism actuating same, it being only essential to have the portion thereof directly behind the shoulders d^5 and behind the releasing means for said plate, projected forwardly as described.

Mounted adjacent to the shoulder d^5 is the lock releasing means f which is of ordinary construction and adapted to be actuated by a knob f' and by the tongue of the cylinder lock f^2 . This releasing mechanism embodies 35 therein a roll-back, as g , adapted to retract the bolt when moved in either direction.

Seated on the bottom of the casing is a 40 sliding plate h having upwardly projected angular studs h' thereon interposed between the roll-back g and the shoulders d^5 of the bolt, the sides of which studs respectively are so shaped as to engage the said shoulders, and beveled so as to pass beneath and 45 actuate the detent, as at h^2 . The top of said studs presents sufficient bearing surface to afford a suitable rest for said plate when it is raised, and the pitch of the bevel and length of this bearing surface are so proportioned 50 relative to the distance between the shoulders d^5 and the forward edge of the plate e that there will be sufficient movement of said sliding plate and its appurtenances with that of the bolt d to raise said dead latch plate 55 before the shoulders d^5 contact with said detent e . The plate h slides on the bottom of the casing a and if required, a way at a^3 through said casing is provided, to permit the required amount of movement of the 60 plate. The casing or plate, however, may be so formed and arranged as to avoid said plate projecting through said casing when it is operated. I use a sliding plate as described to give strength and rigidity to the 65 plate and to insure its being properly posi-

tioned and not susceptible of disarrangement. The bottom of the casing also forms a way for said plate, preventing looseness or lateral movement thereof, and the way a^3 prevents the plate leaving said bottom.

The above described construction normally locks the bolt and permits it to be operated by a key or knob, but means must be provided actuated by the bolt itself, to release said detent when the bolt is latched in closing 70 a door. This means comprises a sliding plate k having a tongue k' passed through the way a^2 and mounted in and projecting considerably beyond, a channel k^2 in the bolt d , as shown in Fig. 4. The plate k has laterally 75 projected arms k^3 within the casing a , which serve to steady said tongue, and to support the cam plate l , through which the detent is actuated by said tongue. A shoulder k^4 on said plate carries a rod or pin k^5 passing 80 through the post a^4 by means of which the closure plate c is secured in place, a spring k^6 being interposed between said shoulder and said post normally causing said tongue to act in synchronism with the bolt d . Either 85 or both arms k^3 have an upwardly extended projection, as m at the end thereof adjacent to the casing a , to which is riveted or otherwise connected or attached, the cam plate l , the end of which is cut away as shown on the 90 upper surface to form the inclined contact face l' projecting into close proximity to the detent e , and extending thereunder.

Directly above the contact l' , the detent e is so formed as to provide a clearance for 100 the projecting end of said contact, and an abutment, dropped below the level of said detent and into the path of said contact, whereby as said arm is reciprocated, the incline thereof will raise said detent through 105 said abutment, or by passing to the clearance space behind said abutment, permit said detent to be positioned so as to prevent movement of the bolt. Preferably I provide such clearance and such abutment by forming up to an arch n with a straight end n' , an integral strip of said detent e .

The socket plate b is of ordinary construction.

The operation of the herein described lock 115 and latch combined, is substantially as follows: When a door is open, the springs d^2 and k^6 project the bolt d and tongue k' through the openings a' and a^2 respectively, the latter projecting from the channel k^2 in 120 the former sufficiently to provide an extended contact face of such width as to compensate for inaccuracies in setting the door, or the settling of the door in its casement. The 125 amount of projection of the said bolt and the said tongue is limited by engagement of the shoulders d^5 with the studs h' the latter being in engagement with the rocking levers of the releasing mechanism. When being so pro- 130

jected, the tongue k' and the projection m thereon draw the cam plate l forwardly, the inclined cam face thereof through engagement with the end or abutment n' raising the 5 detent e on its pivots e^2 until the forward edge thereof is above the shoulders d^5 and the studs h' . As the lock is latched through the engagement of the bevel of the bolt d with the socket plate b , both it and the tongue k' and its appurtenances, are forced inwardly 10 against spring tensions, the shoulders d^5 passing beneath the detent e before the cam face l' passes into the clearance space rearwardly of the abutment n' , the plate h having no movement during this operation. As the door closes, the bolt d is forced outwardly 15 from the casing a into the opening in the socket plate b , the tongue k' being held against movement through contact with the face plate of said socket. Through this 20 movement the shoulders d^5 pass forwardly from beneath the detent e , the cam face l' remaining in the clearance space in said plate, whereby the inner edge of said detent is forced downward with a slight rocking or 25 pivotal movement, by its spring e' until said inner edge is directly behind the shoulders d^5 . This is the position of the parts when the lock is latched. If a knife, strip of steel 30 or other implement be inserted between the lock casing and the socket plate, and pressure be exerted on the beveled side of the bolt, said bolt will recede only until the shoulders d^5 engage the detent e which acts as 35 a positive and definite stop to all further movement. By mounting said detent with the rear edge in close juxtaposition to the casing a , all strains on said detent may be transmitted to the lock casing, thus relieving 40 the pivot pin of such strains. While the lock, when latched, is thus perfectly dead, it may be released by a key, or knob, in the usual manner, the roll-back g being capable of engaging either stud h' and reciprocating 45 the plate h . As said plate h moves through the action of said lever, the bevels h^2 of its studs simultaneously engage the under side of the forward edge of the detent e and by a timely elevation thereof permit the passage 50 of the shoulders d^5 thereunder with the continued movement of the bolt necessary to draw same within the casing. As the releasing mechanism is freed, the bolt d and tongue k' , it being assumed that the bolt is 55 free of the socket plate b , are projected from the casing a synchronously, rendering the detent e inoperative and permitting the latching of the lock as above described.

The organization of the lock shown in the 60 drawings and heretofore described, is such as to adapt the invention to a particular type of lock. It is not my intention to limit the invention to the precise details of construction shown in the drawings, however, as the elements may be varied in their design and rela-

tive positions, without varying the functions and modes of operation thereof, and without departing from the spirit and scope of the invention.

Having described the invention, what I 70 claim as new and desire to have protected by Letters Patent is:—

1. An automatic combined lock and latch comprising a casing, a spring pressed bolt therein, one or more shoulders or abutments 75 on said bolt whereby it may be drawn within said casing, key or knob actuating means for said bolt, a detent adapted when said lock is latched to engage said bolt and prevent movement thereof, means interposed between said shoulders and said first mentioned means, and adapted to release said detent, a reciprocating member adapted to be projected from said casing with the bolt when said bolt is disengaged from the 80 socket, and to engage the edge of the socket and be forced within said casing when the said bolt enters said socket, means actuated by said member whereby when said member is projected, said detent will be rendered inoperative, and when it engages said socket said detent will be set, and a bolt socket.

2. An automatic combined lock and latch comprising a casing, a spring pressed bolt 95 therein, one or more shoulders or abutments on said bolt whereby it may be drawn within said casing, key or knob actuating means for said bolt, a detent adapted when the lock is latched to engage said bolt and prevent movement thereof a 100 slidable plate having 105 studs thereon each comprising a surface engaging one of said shoulders or abutments and a bevel adapted to engage and raise said detent, a reciprocating member adapted to be projected from said casing with the bolt when said bolt is disengaged from the socket, and to engage the edge of said socket and be forced within said casing when the bolt enters said socket, means actuated by 110 said member whereby when said member is projected said detent will be rendered inoperative, and when it engages said socket, said detent will be set, and a bolt socket.

3. An automatic combined lock and latch comprising a casing, a spring pressed bolt 115 therein, one or more shoulders or abutments on said bolt whereby it may be drawn within said casing, key or knob actuating means for said bolt, a detent adapted when the lock is latched to engage said bolt and prevent movement thereof a 120 slidable plate mounted on the bottom of said casing and moving through a slot therein, having studs thereon each comprising a surface engaging one of said shoulders or abutments and a bevel 125 adapted to engage and raise said detent, a reciprocating member adapted to be projected from said casing with the bolt when said bolt is disengaged from the socket, and to engage the edge of said socket and be forced 130

- within said casing when the bolt enters said socket, means actuated by said member whereby when said member is projected, said detent will be rendered inoperative and 5 when it engages said socket, said detent will be set, and a bolt socket.
4. An automatic combined lock and latch comprising a casing, a spring pressed bolt therein, one or more shoulders or abutments 10 on said bolt whereby it may be drawn within said casing, key or knob actuating means for said bolt, a detent adapted when said bolt is latched to engage said shoulders or abutments and prevent movement of said bolt, 15 means interposed between said shoulders or abutments and said first mentioned means, and adapted to release said detent, a slideable cam plate, a spring pressed tongue projected beyond said casing and movable synchronously with and independently of said bolt, 20 connections between said tongue and said cam plate whereby said detent is rendered inoperative when said tongue is projected from said casing, and a bolt socket.
- 25 5. An automatic combined lock and latch comprising a casing, a spring pressed bolt therein, one or more shoulders or abutments on said bolt whereby it may be drawn within said casing, key or knob actuating means for 30 said bolt, a detent having a clearance space therein and an abutment forwardly thereof adapted when said bolt is latched to engage said shoulders or abutments and prevent movement of said bolt, means interposed be- 35 tween said shoulders or abutments and said first mentioned means, and adapted to release said detent, a slideable cam plate, the inclined portion of which is adapted to engage the abutment on and pass to the clearance 40 space in said detent, a spring pressed tongue projected beyond said casing and movable synchronously with and independently of said bolt, connections between said tongue and said cam plate whereby said detent is 45 rendered inoperative when said tongue is projected from said casing, and a bolt socket.
6. An automatic combined lock and latch comprising a casing, a spring pressed bolt therein, one or more shoulders or abutments 50 on said bolt whereby it may be drawn within said casing, key or knob actuating means for said bolt, a detent having a clearance space therein and an abutment forwardly thereof adapted when said bolt is latched to engage 55 said shoulders or abutments and prevent movement of said bolt, means interposed between said shoulders or abutments and said first mentioned means, and adapted to release said detent, a tongue plate slidably mounted in said casing comprising a tongue seated in and projecting from a channel in 60 said bolt, laterally projected arms, a cam plate carried by one of said arms, a shoulder thereon, a rod carried by said shoulder and 65 extending through a fixed stud in said casing,

and a spring interposed between said stud and said shoulder whereby said tongue is normally projected beyond said casing, said cam plate being projected under said detent, the inclined part thereof being adapted to 70 engage the abutment on and enter the clearance in said detent, and a bolt socket.

7. An automatic combined lock and latch comprising a casing, a spring pressed bolt therein, one or more shoulders or abutments 75 on said bolt whereby it may be drawn within said casing, key or knob actuating means for said bolt, a detent pivotally mounted in said casing with one edge thereof adjacent to said shoulders or abutments and the other edge in 80 close juxtaposition to said casing, a spring whereby said detent is normally projected behind said shoulders or abutments whereby when said lock is latched said detent will prevent movement of said bolt, a slideable plate 85 having studs thereon each comprising a surface engaging one of said shoulders or abutments and a bevel adapted to engage and raise said detent against the tension of its spring, a reciprocating member adapted to 90 be projected from said casing with the bolt when said bolt is disengaged from the socket, and to engage the edge of said socket and be forced within said casing when the bolt enters said socket, means actuated by said member 95 whereby when said member is projected said detent will be rendered inoperative, and when it engages said socket, said detent will be set, and a bolt socket.

8. An automatic combined lock and latch 100 comprising a casing, a spring pressed bolt therein, one or more shoulders or abutments on said bolt whereby it may be drawn within said casing, key or knob actuating means for said bolt, a detent having a clearance space 105 therein and an abutment forwardly thereof, adapted when said bolt is latched to engage said shoulders or abutments and prevent movement of said bolt, a slideable plate having studs thereon each comprising a surface 110 engaging one of said shoulders or abutments and a bevel adapted to engage and raise said detent, a slideable cam plate, the inclined portion of which is adapted to engage the abutment on and pass to the clearance space in 115 said detent, a spring pressed tongue projected beyond said casing and movable synchronously with and independently of said bolt, connections between said tongue and said cam plate whereby said detent is rendered 120 inoperative when said tongue is projected from said casing, and a bolt socket.

In witness whereof, I have hereunto affixed my signature this 29th day of August, 1906, in the presence of two witnesses.

FRANK S. ALIANO.
